DESIGN FOR A SHOE

Joseph McGee, New York, N. Y., assignor to Bancroft-Walker Company, Waltham, Mass., a corporation of Massachusetts

Application May 29, 1936, Serial No. 62,904

Term of patent 3½ years

To all whom it may concern:

Be it known that I, Joseph McGee, a citizen of the United States, residing in New York, in the county of New York and State of New York, have invented a new, original, and ornamental Design for a Shoe, of which the following is a specification, reference being had to the accompanying drawing, forming a part thereof, in which—

Fig. 1 is a plan view of a shoe showing my new design,

Fig. 2 is a view of the shoe in side elevation.

I claim:

The ornamental design for a shoe substantially as shown.

In testimony whereof, I have affixed my signature hereto.

JOSEPH McGEE.
